UNITED STATES PATENT OFFICE.

HENRY W. O'NEILL, OF BROOKLYN, NEW YORK, ASSIGNOR TO WESTERN ELECTRIC COMPANY, INCORPORATED, OF NEW YORK, N. Y., A CORPORATION OF NEW YORK.

TELEGRAPH SYSTEM.

Application filed November 19, 1919. Serial No. 339,093.

To all whom it may concern:

Be it known that I, HENRY W. O'NEILL, a citizen of the United States, residing at Brooklyn, in the county of Kings, State of New York, have invented certain new and useful Improvements in Telegraph Systems, of which the following is a full, clear, concise, and exact description.

This invention relates to telegraph systems.

An object of the invention is to provide a system for improving the wave form of the signal current impulses transmitted over signaling conductors having a high electrostatic capacity.

In signaling over conductors of high electrostatic capacity, such as submarine cables, the time required for the transmission of a given number of impulses will vary almost directly in proportion to the capacity and resistance of the line circuit.

The resistance and inductance of terminal apparatus, the time constant of operation of relays or other receiving devices and the potential and manner of applying transmission currents to a line conductor are all factors which play a part in affecting the rate of transmission or the degree of efficiency at which a signaling circuit may be operated.

It is common practice to so proportion the various parts of a signaling circuit and the potentials of the currents employed, that following an application of current at the sending end of a line the receiving devices at the distant end will respond on the instant the potential of the circuit reaches a strength equal to approximately two-thirds of the final or steady current value possible after the current has become equalized in the circuit. The current in excess of two-thirds of a final steady potential value in a line circuit represents the factor of safety.

The greater the inductance or the more efficient the magnetic circuit of a relay the higher the time constant of its operation, and in relays of commonly accepted design the efficiency of the magnetic circuit is appreciably increased when the armature is in its attracted position. In case the relay is subjected to an energizing current of maximum potential for other than relatively short periods, the increased density of the

magnetism created therein will cause a slow release of the armature on cessation of the energizing current.

From the foregoing it will be clear that continuation of current beyond the point where it has attained its full or steady current value in a signaling circuit necessarily results in an excessive charging of the line conductor proper and also in the setting up of unnecessarily high density in the magnetic circuits of the relays or other terminal equipment. These conditions accordingly result accumulatively in reducing the speed at which signals may be transmitted over a circuit.

The increasing employment of underground and aerial cables necessary in the joining up of land lines, results in placing such lines relatively in the category of cable circuits. Therefore, as will presently appear the present invention may also be employed to advantage on such land circuits.

The foregoing observations make it clear that for a circuit in which the electrical characteristics of the terminal apparatus and the line conductor bear a proper relation, a relatively high potential current may be applied to the line and that following the instant when the current reaches its steady value, the potential may be reduced advantageously. This reduction of the current strength may take place considerably in advance of the expiration of a period allotted to a signaling impulse interval, and in order that the receiving devices may be retained in the position to which they may have been operated the polarity of the current of low potential should be the same as the polarity of the high potential current for which it may have been substituted.

For convenience, the high potential currents may be referred to as "control" currents or currents at control potential, while the low potential currents may be referred to as "holding" currents or currents at holding potential. Many relays or receiving devices are of such design that after being operated the device will retain its armature under the influence of a relatively weak holding current. In many instances this holding current may have a strength equal to only ten percent of the strength of the

control current necessary for first operating the device. It will also be clear that in double current working and in the control of telegraphic printers through permutations of positive and negative impulses, a further improvement in transmission may be had by providing that after a first impulse interval any immediately following or successive impulse intervals requiring a like polarity may be represented by continuance of the low potential holding current as applied during the latter portion of the first impulse interval in such a series. This elimination of the high potential control currents during successive repetition of impulses of like polarity prevents an undue charging of the line conductor and also avoids the building up of unnecessary magnetic flux in the receiving devices, each of which effects would have a tendency to retard the transmission of signals as already mentioned. In order that any tendency to asymmetrical charging of a line even to a relatively limited extent as may possibly occur from a prolonged application of holding current of one polarity as described, it will now be further clear that if the line conductor is switched to earth following such an application of holding current the circuit may thereby be drained to a proper zero current condition.

In line with the features above pointed out as desirable in the efficient operation of signaling circuits, the present invention contemplates an arrangement of transmitting apparatus including electroresponsive switching devices, whereby transmission currents may be controlled in such a manner that in addition to expediting the charging and discharging or the effecting of current variations in a line conductor proper, the responses of the receiving devices may also be accelerated to a corresponding degree, thereby maintaining a proper interrelation between the various factors entering into the operation of a complete circuit.

This invention is illustrated diagrammatically in the accompanying drawing in which, for the sake of clearness, only so much of the telegraphic transmitting system has been shown as will be necessary to a clear understanding of the features of the invention.

Fig. 1 illustrates a transmitting system suitable for practicing the features of this invention; Fig. 2 illustrates an alternate arrangement of the system shown in Fig. 1, while in Fig. 3 is shown an arrangement whereby the present invention may be employed in multiplex telegraph working in a manner suitable for the control of telegraphic printing operations.

In describing this invention reference will first be had to Fig. 1 of the drawing wherein a transmitter 1 may be worked to close either the contacts 2 or the contacts 3

in applying the respectively associated positively and negatively poled sources of current to operate two relays 4 and 8. A condenser 7 connected in series with the relay 4 renders the responses of this relay of short duration only, while the relay 8 may continue operated so long as current may be applied thereto. Each response of the relay 4 separates its contacts 5 to disconnect a line conductor L from the circuit normally established to earth at the normal contact of the relay 8, while closure of the contacts 6 apply the current which may have been selected by the transmitter 1 to the line L. The equalizing of current effects in the condenser 7 permit the relay 4 to release and switch the line conductor L by way of the contacts 9 of the relay 8 and an adjustable resistance 10 to the source of current which may have been selected at the transmitter. On the transmitter being released deenergization of the relay 8 again switches the line conductor to the earth connection. It will therefore be obvious that on the instant the transmitter is operated high potential or control current from the source selected may be momentarily connected to the line and immediately following this, before the transmitter is released, holding current as reduced in potential by the resistance 10 will be substituted for the control current.

The contacts of the relay 4 are of the so-called "make-before-break" type in order that cessation of current will not take place during moments the armature of the relay may be in motion in switching the line from the control to the holding current supply leads. A resistance 11 prevents excessive flow of current in the local circuit during instants the members forming the contacts 5 and 6 may all be in engagement, one with the other.

In situations where it may be desired to employ so-called single current working, one of the sources of current may be dispensed with and, in order that the condenser 7 may be relatively emptied between successive applications of current of the same polarity, a switch 15 may be closed to establish a "leak" circuit from the transmitting lead to earth through an associated resistance. This arrangement of single current working will establish the two different current strengths with the line conductor during each impulse interval as already described for the double-current working, and intermediate successive impulses the line will be grounded through the releasing of the relay 8.

The arrangement shown in Fig. 2 differs from that shown in Fig. 1 principally through the use of a polarized relay 12 which is connected in series with the relay 8. This permits the resistance 10 to be dispensed with and in substitution thereof de-

rived circuit points 16 and 17 are provided on the positive and negative batteries respectively. At proper moments energization of the relays 8 and 12 from the positive battery permit low potential holding current to flow from the point 16 by way of the contacts 13, 9 and 5 of the respective relays 12, 8 and 4 to the line conductor L, and during corresponding energization of the relays 8 and 12 from the negative battery low-potential holding current may flow from the point 17 by way of the contacts 14, 9 and 5 of the respective relays to the line. As shown, the line will stand connected to earth at the normal contacts of the relay 8 during periods the transmitter 1 may be out of engagement with the sources of current.

In Fig. 3 a multiplex distributor, preferably of a suitable rotary type, is shown in developed form and comprises collector rings 19 and 20, segments 21 to 25 and contactor arms or brushes 26 and 27. Switching levers 31-35 represent contacts to be controlled by means of a keyboard or a transmitting tape (not shown) and serve to prepare permutations of current polarities from the associated positive and negative sources for energizing the segments. The brushes 26 and 27 traverse their respective paths from left to right and the brush 26 successively joins the segments 21-25 to the ring 20 and current present on the segments may control the relays 4 and 12 in a manner similar to that already described for the corresponding relays, Fig. 2. The brush 27 is so spaced with respect to the brush 26 that it may just be entering upon a segment, as the segment 22, at an instant the brush 26 may be just leaving the next last segment, as the segment 21. The brush 27 applies current from the segment 21-25 to the ring 19 to control the relay 8. In this arrangement the latter relay is to be of a suitable "slow-releasing" type in order that its armature may be retained during periods the brush 27 may be traversing the space intermediate adjacent segments. The relay 8 will therefore continue in its operated position except during moments corresponding with the collapse of magnetism therein due to a reversal of current through its winding. This insures that no interruption of low potential holding current from the point 16 or 17 as routed through the contacts of the relay 12 and the forward contacts 9 of the relay 8 may take place during prolonged intervals corresponding with successive impulses of like polarity as already described. At an instant the brush 27 may encounter a segment energized by current having polarity inverse to the current present on the segment last traversed by this brush, the necessary reversal of magnetism will be established in the relay 8 to cause it to momentarily release and connect the line L to

earth. On the instant the magnetism of this relay builds up in the opposite sense in conformity with the current present through the brush 27, the relay will respond and close its contacts 9. In this multiplex arrangement it will be understood that character selection impulses may be in accordance with the well-known five unit code of Baudot.

Although the contacts of the relays 4 in Figs. 2 and 3 have been shown as of the "break-before-make" type it will be understood that these relays may be of the "make-before-break" type as shown and already described in connection with the corresponding relay 4 of Fig. 1.

It will be understood that the transmitter 1 of Figs. 1 and 2 may be manipulated in a manner to continue an energization of the line by current of one polarity during periods corresponding with successive impulses of like polarity. Therefore, these equipments may effect continuous applications of holding current to the line to the exclusion of high potential currents during intervals corresponding with a second and any additional successive impulses of like polarity. The relays 8 of Figs. 1 and 2 may be adapted to respond relatively in phase with the transmitters 1, and, therefore, it will be clear that the line may be switched to earth intermediate impulses of opposite polarity in double-current working and to earth intermediate all impulses in the single current working as already described.

Through the present invention the application of printing telegraph service may be made to cable conductors otherwise having a time constant of operation which would render the transmission rate or speed of sending too slow for commercial service.

What is claimed is:

1. A telegraph system comprising a line circuit, a source of signaling current, an impulse transmitting device, a relay responsive to the actuation of said transmitting device to connect said line circuit to said source of current, a condenser in series with said relay to limit the period of energization thereof, another relay also responsive to the actuation of said transmitting device, and contacts controlled thereby to apply signaling current of lessened potential to said line upon the deenergization of said first relay.

2. In a telegraph system a line circuit, a source of signaling current, a pole changer connected thereto, a relay and a condenser in series, circuit connections whereby an operation of said pole changer causes an impulse of current to flow through said relay to charge said condenser and thereby to cause a momentary operation of said relay, contacts closed by the operation of said relay to connect said line circuit to said pole changer and thereby to apply current of a definite po-

larity and potential to said line circuit, another relay also responsive to the actuation of said pole changer and contacts controlled thereby for applying current of the same polarity but of lessened potential to said line circuit upon the deenergization of said first relay.

3. In a telegraph system, a line circuit, sources of current, first and second relay means and a control circuit therefor, electro-inductive means included with said control for rendering the responses of said first re-

lay means of shorter duration than the responses of said second relay means, and circuits jointly controlled in the operation of 15 said first and second relay means for successively applying currents of different potentials from said sources to said line without permitting cessation of current in the line.

In witness whereof, I hereunto subscribe 20 my name this 17th day of November A. D., 1919.

HENRY W. O'NEILL.
